Inventor:
James S. Thompson
By: Wm. C. Bell, Atty.

UNITED STATES PATENT OFFICE.

JAMES S. THOMPSON, OF PELHAM, NEW YORK.

BRAKE-SHOE MOLD.

Application filed July 20, 1923. Serial No. 652,779.

To all whom it may concern:

Be it known that I, JAMES S. THOMPSON, a citizen of the United States, residing at Pelham, in the county of Westchester and 5 State of New York, have invented certain new and useful Improvements in Brake-Shoe Molds, of which the following is a specification.

This invention relates to the manufacture 10 of brake shoes, and more particularly to the mold in which the shoe is cast, and its object is broadly to provide a permanent mold in which a brake shoe may be cast fully as well as it can be cast in a sand mold, and 15 with accompanying reductions in time and cost.

A further object of my invention is to provide a permanent mold which can be easily and quickly opened and closed to permit 20 the operator to quickly insert the reinforcing part or parts which are to be embedded in the shoe casting, and to facilitate removal of the shoe.

A still further object of my invention is 25 to provide a metal mold of the character described, having means for protecting all or certain parts of the shoe from the chilling effect which would result by contact of the hot metal with the metal walls of the mold 30 cavity.

Other objects of my invention will become 35 apparent as the detail description progresses, reference being had to the accompanying drawing which illustrates a selected embodiment of the invention, and wherein—

Fig. 1 is a central transverse section through a metal mold embodying the novel features of my invention.

Fig. 2 is a longitudinal section taken on 40 line 2—2 of Fig. 1, and

Fig. 3 is a horizontal section taken on line 3—3 of Fig. 2.

In the drawing I have shown a metal mold comprising a drag member 10, two cope 45 members 11 and 12 having a mold cavity 13 therein, and a relatively fixed frame 14. The drag member 10 is provided with outstanding side lugs 15 which are pivotally connected by means of a pivoting bar 16 to the 50 relatively fixed frame 14. In a like manner, the cope member 11 is provided with outstanding side lugs 17 which are pivotally connected by the pivoting bar 16 to the relatively fixed frame. The cope member 55 12 has outstanding side lugs 18 which are pivotally connected by a pivoting bar 19 to

the frame. It will be readily understood that the drag member 10 and the cope members 11 and 12 may be swung into positions indicated by dotted lines in Fig. 1. To hold the drag 60 member 10 in its closed position, I have provided it with side lugs 20 which are adapted to engage the pivoting bar 19 and which may be secured thereto by means of locking pins 21. The two cope members are held in 65 closed position by clamps 22, the clamps 22 being pivotally secured to the cope member 11 and having threaded posts 23 adapted to engage the cope member 12.

The relatively fixed frame 14 may be supported by any suitable means. In the drawing I have shown the frame 14 as comprising a plurality of integral legs 24 adapted to support the frame upon a table or the like, it being understood that the table or 75 the like would be adapted to permit the drag member 10 to swing downward into its open position.

Each of the cope members 11 and 12 has a part of the mold cavity 13 formed therein, 80 the parting line between the cope members extending longitudinally of the mold and substantially central of the mold cavity. This construction enables the mold to be quickly and easily opened and closed and 85 it also enables the parts which are embedded in the shoe casting to be arranged in the mold and held therein in proper positions. The cope members may be closed without injury to and without disarranging the parts 90 to be embedded in the shoe casting, and they may be opened for the removal of the shoe casting without damage to any parts of the mold.

I have designated by the reference characters 26 and 27, respectively, a steel attaching lug and the steel reinforcing back such as are usually embedded in the shoe casting. The reference character 28 designates a sand core for forming the opening 100 in the attaching lug. It will be noted that the sand core 28 serves to hold the steel attaching lug 26 and the steel reinforcing back 27 in an assembled condition; therefore, the several parts, the attaching lug 26, the reinforcing back 27, and the sand core 28 may be inserted in the mold cavity as a unit and a plurality of wire ties 29 may be employed to hold them in proper positions in the mold cavity. In the preferred embodiment of my 110 invention I provide a sand plug 30 which is recessed at 31 to receive the attaching lug

26 and the sand core 28. The wire ties 29 are suspended from a bar 32 which rests upon a container or holder 33 in which the sand plug 30 is made. The cope members 5 11 and 12 are provided with an opening 34 adapted to receive the holder 33.

When preparing the mold for the casting operation, the operator first closes the cope members 11 and 12 and secures them 0 in their closed positions by means of the clamps 22. The holder 33 containing the sand plug 30 and having the wire ties 29 embedded therein is then inserted into the opening 34 formed in the cope members.

5 The reinforcing unit is then properly positioned in the mold cavity and secured in place by twisting the ends of the wire ties 29, after which the operator need only bring and secure the drag member 10 to and in its 20 closed position to have the mold ready for the casting operation.

I have provided the mold with refractory sections of improved form which are adapted to hold the brake shoe to be cast in the 25 mold free from the chilling effect which would result by contact of the hot metal with the metal walls of the mold cavity. The bottom wall of the mold cavity is formed by a refractory section 35 secured 30 in the drag member 10. Each of the cope members 11 and 12 is provided with a refractory section 37 adapted to form portions of the end walls, side walls, and the top walls of the mold cavity. The several refractory sections and the sand plug 30 are 35 so formed that the hot metal poured into the mold cavity does not come in contact with a metal wall. The shoe cast in the mold would have a substantially uniform texture throughout its body. However, the 40 mold can be made to produce a shoe having an integral composite wearing face. This result can be obtained by altering the design of the refractory sections to have 45 the hot metal come in contact with the metal of the mold so that certain portions of the shoe will be subjected to the chilling effect thereof.

This invention provides a metal mold in 50 which a brake shoe may be cast fully as well as it can be cast in a sand mold, and in less time. It is apparent that the mold can be closed without the exercise of special skill or any considerable amount of 55 labor. I have indicated a pouring gate at 38, the lower end of the pouring gate registering with an opening in the steel back 27.

My invention can be employed for making 60 castings other than brake shoes and I consider myself entitled to make all such changes in the form, construction and arrangement of parts as may be necessary or desirable for this purpose, and for making 65 different kinds, shapes and sizes of brake

shoes, which fairly fall within the scope of the following claims.

I claim—

1. A permanent mold for making castings, comprising a frame, a drag pivotally mounted on the frame, and a two-member cope, each of said cope members being pivotally mounted on the frame. 70

2. A permanent mold for making castings, comprising a frame, a drag pivotally 75 mounted on the frame and a two-member cope, each of said cope members being pivotally mounted on the frame and having a part of the mold cavity therein.

3. A permanent mold for making castings, comprising a frame, a drag pivotally 80 mounted on the frame, and a two-member cope, each of said cope members being independently pivoted upon the frame and having a part of the mold cavity therein. 85

4. A permanent mold for making castings, comprising a frame, a drag pivotally 90 mounted on the frame, a two-member cope, each of said cope members being pivotally mounted on the frame and having a part 95 of the mold cavity therein, and a sand plug seated in an opening formed in said cope members.

5. A permanent mold for making castings, comprising a frame, a drag pivotally 100 mounted on the frame, a two-member cope, each of said cope members being pivotally mounted on the frame and having a part 105 of the mold cavity therein, a sand plug, and means embedded in the sand plug for suspending in the mold cavity the parts which are to be embedded in the casting.

6. A metal mold for casting a brake shoe, comprising a frame, a drag pivotally 110 mounted on the frame, a two-member cope, each of said cope members being pivotally mounted on the frame and having a part of the mold cavity therein, a sand plug seated in the cope and having a recess therein to receive the core for forming the opening in the attaching lug of the shoe, and means extending through the sand plug for supporting in the mold cavity the parts which are to be embedded in the casting.

7. A permanent mold for making castings, comprising a frame, a drag pivotally 115 mounted on the frame, a two-member cope having an opening extending therethrough, part of the opening being formed in one of said cope members and another part of the opening being formed in the other of said cope members, each of said cope members being pivotally mounted on the frame, a sand plug seated in said opening, and means carried by the sand plug for supporting in 120 the mold cavity the parts which are to be embedded in the casting.

8. A permanent mold for making castings, comprising a drag and a two-member 125 cope having a mold cavity therein, said 130

cope members being movable independently and relatively to the drag, said cope having an opening therein formed partly in one member and partly in the other, a sand plug in said opening, and means embedded in said sand plug for suspending in the cavity the parts to be embedded in the casting.

9. A permanent mold for making castings, comprising a drag and a two-member cope having a mold cavity therein, said cope members being movable independently and relatively to the drag, said cope having an opening therein formed partly in one member and partly in the other, a sand plug in said opening, and means extending through said sand plug for suspending in the mold cavity the parts to be embedded in the casting.

10. A permanent mold for making castings, comprising a drag and a two-member cope having a mold cavity therein, said cope members being movable independently and relatively to the drag, said cope having an opening therein formed partly in one member and partly in the other, a sand plug in said opening, and means carried by said sand plug for supporting in the cavity the parts to be embedded in the casting.

11. A permanent mold for making cast-

ings, comprising a frame, a drag pivotally mounted on the frame, a two-member cope, said cope members being movable independently and relatively to the drag, said cope having an opening therein formed partly in one member and partly in the other, a sand plug in said opening, and means carried by said sand plug for supporting in the mold cavity the parts to be embedded in the casting.

12. A permanent mold for making castings, comprising a frame having an opening therein, a cope, a drag pivotally mounted on the frame at one side of said opening to swing into operative position in said opening, and means for securing the drag in operative position.

13. A permanent mold for making castings, comprising a frame having an opening therein, a two-member cope, each of said cope members being pivotally mounted on the frame and adapted to abut in operative position and to be supported and rest upon the frame in open position, a drag pivotally mounted on the frame and adapted to be swung up in said opening in abutting relation to the cope members, and means for holding said drag in abutting position.

JAMES S. THOMPSON.
